CHARLES L. STOELTZLEN, OF ERIE, PENNSYLVANIA, ASSIGNOR TO BURKE ELECTRIC COMPANY, A CORPORATION OF PENNSYLVANIA.

SWITCH LOCK.

Application filed October 1, 1924. Serial No. 740,973.

This invention relates to switches and particularly to switches which are subjected to heavy overloads tending to blow open the switch and break the circuit. Such unintended breaking of the circuit is often attended with dangerous arcing and violent surging of the line.

The object of this invention is to provide a switch lock which will hold the switch closed against accidental opening and at the same time will not interfere with the intentional opening and closing of the switch. A further object of the invention is to provide such a switch lock which may be readily attached to installed switches without dismantling or machine work.

In the accompanying drawings illustrating the invention.

Fig. 1 is an elevational side view of a switch lock embodying the invention, and

Fig. 2 is a sectional view on the line 2—2 of Fig. 1.

In the specific embodiment of the invention shown in the drawings a blade switch has a stationary member 3 carried, for instance, by a wall bracket 4 or supported in any desired manner. The movable switch part is designated 5, only the upper end being shown, the lower end being mounted on a pivot in the usual manner so that the blades 5 move into and out of contact with the stationary leaves 3 along the line of the arc indicated by dotted line 6. This may be considered to exemplify the usual type of blade switch.

To hold this switch against unintentional opening the lock parts are carried by the stationary and movable parts of the switch. On the base of the stationary part 3 are clamped the horizontal clamping bars 7, 8 drawn together by bolts 9 to grip the switch base between them. The lower clamping bar 8 carries the downwardly projecting bracket arms 10 which at their lower ends support the horizontally extending locking pin 11 thus held in stationary position with relation to the switch.

Fastened at the movable switch member 5 are the side plates 12, 13 tightly clamped in place by bolts 14 as shown; each plate 12, 13 carries a stub shaft 15 upon which is pivoted a locking pawl 16 on each side. Each pawl 16 is resiliently drawn downward by a spring 17 so as to hold the hook 18 of the pawl in locking engagement with the

pin 11 and thus prevent the switch 5 from opening.

To release the pawls from locking engagement and open the switch 5 a yoke shaped member 20 is provided having each of its side portions pivoted upon the stub shafts 15 and normally resting with its pins 21 against the stops 22 of the pawls 16, the springs 17 being sufficiently strong to support the weight of the yoke and its connected parts without yielding. The yoke 20 carries a handle or a loop 23 as shown in the drawings adapted to be reached by a suitable instrument and drawn downward and outward to release and open the switch. During this opening movement pivotal movement of the yoke 20 around the axis of the stub shafts 15 tips the hook ends 18 of the pawls 16 upward by the pressure of the pins 21 against the stops 22 so as to release the hooks 18 from the ends of the locking pin 11. This pivotal movement of the yoke 20 and pawls 16 is stopped by engagement of the stops 25 of the pawls against the pins 26 of the side plates 12, 13. Thereupon a further pull on the loop 23 will pull open the switch member 5.

To close the switch the loop 23 is pushed upward so as to pivot the hook 20 clockwise around the stub shafts 15 and this brings the stops 27 of the yoke against the pins 26 of the side plates 12, 13 so that the yoke becomes rigid with these side plates. Further upward pressure on the loop 23 will close the switch, the hook ends 18 of the pawls 16 riding up over the ends of the pin 11 by engagement of the inclined surfaces 28 with said pin. The spring 17 then draws the pawls down into locking engagement with the pin 11 as shown.

The switch lock of this invention is simple in form and easily adapted to various forms of switches, and readily attached to the switch without removing the same and without expensive machine work. It is only necessary to clamp one part on the stationary part of the switch and the other part on the movable part of the switch. There is no interference with the cooperating stationary and movable parts and no alteration of these parts. The switch lock is conveniently positioned between the switch pivot and the contact area and there is no interference whatever with the cooperating contact making portions of the switch.

I claim:

1. The combination with a switch comprising a stationary and a movable part, a clamp attached to the stationary part and carrying a stationary locking member comprising a locking pin, the ends of which extend beyond the stationary part, a clamp fastened to the movable member, a spring pressed movable member comprising two complementary plates carried by said second mentioned clamp and cooperating with the ends of the stationary locking pin to lock the switch in closed position, and an operating member carried by said second mentioned clamp and engaging said movable member to release said lock and permit the switch to be opened.
2. The combination with a switch comprising a stationary and a movable part, a stationary locking member comprising a locking pin, a clamping means fastened to the movable member, a spring pressed locking member carried by said clamping means comprising two pawl members adapted to cooperate with said locking pin to lock the switch in closed position, and an operating member carried by said clamping means and engaging said movable locking member to release said lock when moved in one direction to open the switch and releasing said movable member for locking action when moved in the opposite direction.
3. The combination with a switch comprising a stationary and a movable part, a clamp attached to the stationary part and carrying a stationary locking member, a clamp fastened to the movable member, complementary spring pressed movable members pivoted on stub shafts carried by the said second mentioned clamp and cooperating with the stationary locking member to lock the switch in closed position, and an operating yoke member pivoted to said stub shafts and engaging said movable members to release said lock and permit the switch to be opened.
4. The combination with a switch comprising a stationary and a movable part, a stationary locking member comprising a locking pin extending beyond the stationary part, a clamping means removably fastened to the movable member comprising complementary plates having stub shafts, a spring pressed locking member comprising complementary members pivoted on said stub shafts, and an operating yoke member pivoted on said stub shafts and engaging said complementary members to release said lock when moved in one direction to open the switch and releasing said movable member for locking action when moved in the opposite direction.
5. The combination with a switch comprising a stationary and a movable part, a stationary locking member, a clamping means comprising two complementary plates adapted to clamp the movable member therebetween, a spring pressed locking member carried by said clamping means, and an operating member carried by said clamping means and engaging said movable locking member to release said lock when moved in one direction to open the switch and releasing said movable member for locking action when moved in the opposite direction.

CHARLES L. STOELTZLEN.
